SAFETY CLAMP

Robert F. Normandin, Columbus, Ohio

Application August 31, 1956, Serial No. 607,533

7 Claims. (Cl. 24—252)

(Granted under Title 35, U.S. Code (1952), sec. 266)

The invention described herein, if patented, may be manufactured and used by or for the Government for governmental purposes, without payment to me of any royalty thereon.

This invention relates to an improvement in clamps for releasably joining layers of cloth fabric or the like.

An important object of this invention is to provide a new and improved clamp for joining layers of cloth lying in the same plane but orientated in various directions within the plane such as occurs with a child's diaper and a tab extending from the lower edge of the child's undershirt.

Another object is to provide a new and improved clamp having a shape which is unlikely to pass through a child's esophagus and therefore unlikely to be swallowed by the child.

A further object is to provide a new and improved clamp having a rounded body which allows it to roll with the body movements of the wearer and does not cause irritation of the skin.

A further object is to provide a new and improved quickly releasable clamp with a minimum of projections and crevices which would tend to make it unsanitary.

Another object of the invention is to provide a new and improved clamp including at least one fixed clamping jaw and movable clamping means to cooperate therewith which is movable toward and from clamping relationship with the fixed jaw with a variable force, the magnitude of which may be varied or controlled by the user of the clamp.

Other objects, capabilities and advantages of the invention will become apparent during the course of the following description wherein reference is made to the accompanying drawing, forming a part of this application, in which like numerals are used to designate like parts throughout the same and in which:

Figure 1 is a perspective view of a preferred embodiment of the present invention showing layers of cloth being clamped thereby;

Figure 2 is a side elevation view of the clamp shown in Figure 1;

Figure 3 is an end elevation view of the clamp shown in Figure 1;

Figure 4 is a vertical longitudinal section taken along line 4—4 of Figure 3;

Figure 5 is a plan view of the embodiment shown in Figure 1;

Figure 6 is a perspective view of another embodiment of the invention showing layers of cloth being clamped thereby;

Figure 7 is a plan view of the embodiment shown in Figure 6 on an enlarged scale;

Figure 8 is a plan view of this embodiment showing layers of cloth being clamped thereby with a portion of the clamp broken away to show the means for biasing the movable clamping means;

Figure 9 is a plan view of the same embodiment showing the movable clamping means in inoperative position with a portion of the body broken away to show the

2

means for limiting movement in one direction of portions of the movable clamping means.

Figure 10 is a fragmentary vertical transverse section taken along line 10—10 of Figure 7, and

5 Figure 11 is a fragmentary vertical transverse section of a further modification of the invention taken on the plane of a line corresponding to the line 11—11 in Figure 8.

Referring now to the drawing wherein for the purpose 10 of illustration, Figures 1 through 5 show a preferred embodiment of the invention, the improved clamp of the present invention comprises a body portion generally designated by the number 12 which is preferably formed from a unitary section of clear plastic or lightweight metal 15 and a movable clamping member, preferably of the same material, designated by the numeral 13.

The clamp body 12 comprises a generally U-shaped portion defining generally parallel opposed legs 14 and 15, of substantially rectangular cross section, joined at 20 one end by an arcuate portion 16 as shown in Figures 1 and 3 which is also of rectangular cross section as shown in Figure 4. The inner surface of this arcuate portion 16 is conformed to define a generally circular aperture 17 which communicates with the space between the opposed 25 legs 14 and 15 providing a terminal enlargement of this space to receive seams or excess material on the cloth to be clamped. The free ends of said legs 14 and 15 have opposed arms or projections 18 and 19 extending therefrom in the same direction and in parallel planes at 30 approximately a right angle with said legs as shown in Figures 2 and 4 so as to define fixed jaws disposed in opposed spaced relation. These arms are preferably of equal length and of generally rectangular cross section gradually decreasing in thickness toward their free ends. 35 It will thus be seen that the clamp body 12 comprises duplicate body members each conformed to define substantially right angularly disposed portions interconnected at a single region remote from the juncture of the angularly disposed portions so that the angularly extending portions 18 and 19 form fixedly spaced jaws.

The opposed inner surfaces of the legs 14 and 15 and fixed jaws 18 and 19 with the exception of the surfaces forming terminal enlargement 17 are preferably provided with a friction surface such as the serrations 20 shown in Figures 1 and 4 of the drawing to improve the gripping action of the clamp on the cloth or like material to be clamped.

The movable clamping member 13 may be similar to a flat headed machine screw or the like and it is threaded 50 into an aperture in the fixed jaw 18. At its inner end, the clamping member 13 is preferably slightly upset as best shown in Figure 5 after being threaded into jaw 18 to prevent its inadvertent disengagement therefrom and to increase the surface area thereof bearing against the material to be clamped.

In the operation of this embodiment of the present invention, the movable clamping member 13 is backed off sufficiently so that the layers of material 22 to be clamped may be received in the space between the fixed jaws 18 60 and 19, care being taken to make certain that some portion of each layer of material to be clamped lies in that portion of the opening between the movable clamping member 13 and the portion of the fixed jaw 19 opposed thereto. The clamping member 13 is then advanced toward jaw 19 by rotation thereof with respect to the clamp body a sufficient number of turns to firmly engage the materials 22 between said clamping member and the opposed surface of fixed jaw 19. It will be noted 65 that this clamping action may be achieved by relatively few turns of the clamping member 13 depending upon the thickness of the materials to be joined and the extent to which the clamping member is withdrawn prior to the

insertion of the materials. It should be further noted that the friction surface 20 affords additional strength to the gripping action of the clamp.

The release of materials being clamped is accomplished by merely withdrawing the movable clamping member 13 by turning same and removing the clamp from the materials.

The embodiment of the invention shown in Figures 6 through 10 includes a clamp body 23 and movable clamping means designated as an entirety by the number 24. The clamp body 23 is generally similar in construction to the clamp body 12 of the first embodiment of the invention and includes elongated arms or jaws 25 and 26 and a generally U-shaped portion 27 interconnecting the jaws 25 and 26 adjacent one end thereof and fixedly holding the same in opposed spaced relation so that one face of jaw 25 is opposed to the corresponding face of jaw 26.

The movable clamping means 24 comprises a pair of arms 28 and 29 both pivoted to swing independently of each other on a single pin 30 anchored in the fixed jaw 25 at the end thereof connected to the U-shaped portion 27 as shown in Figure 7. Arms 28 and 29 preferably are cast from a lightweight metal or may be formed from sheet metal of channel shape in cross section. Each of these arms has a bifurcated end for embracing the fixed jaw 25 and engaging upon the pin 30 (Figure 10) pivotally to connect these arms to the clamp body 23, the arm 28 being swingable in the space between the opposed faces of fixed jaws 25 and 26 and the arm 29 being swingable toward and from the side of jaw 25 opposite its opposed face into and out of nested or jackknifed relation with this opposite side as shown in Figures 8 and 9.

The first arm 28 has a portion 31 on its free end of substantial extent disposed at an angle to the pivoted end thereof and conformed to be disposed in a plane approaching parallelism with the plane of the opposed face of fixed jaw 26 when this first arm is in operative position so as to cooperate therewith in clamping material to be held by the clamp. This first arm thus constitutes the movable clamping member or jaw of this clamp. Preferably the fixed jaw 25 is recessed to receive the second swinging arm 29 in nested or jackknifed relation, and this second arm has a locking lug or clip 32 formed thereon which is adapted to snap into and out of a complementary recess 33 in the fixed jaw 25 releasably to hold the swinging arm 29 in nested or jackknifed position.

Reacting between the first swinging arm or clamping jaw 28 and swinging arm 29 is an expansion spring 34 which biases these two parts in opposite angular directions. This spring is housed in a pair of telescopically interconnected tubular members 35 and 36, the member 35 being anchored to the swinging arm 29 and the member 36 to the swinging jaw 28. These telescopic members are of arcuate shape in an end to end direction on a radius centered on the pivot pin 30 so that they will telescope without binding when the swinging jaw 28 and swinging arm 29 are rocked on the pin 30, and the fixed jaw 25 has an arcuate bore or passage through which the telescopic member 35 freely passes. To limit outward swinging movement of the swinging arm 29, the telescopic member 35 is provided with a bead 37 on its free end for engaging on the bottom of a counterbore 38 in the fixed jaw 25. Telescopic member 36 is of sufficient length so that it will remain engaged in member 35 when swinging jaw 28 and arm 29 are at the outer limit to which they are movable from each other as shown in Figure 9.

The opposed surfaces of fixed jaw 26 and swingable clamping jaw 28 are preferably provided with friction surfaces such as the serrations 39 shown in Figures 7, 8 and 9 of the drawing to improve the gripping action of the clamp on the materials clamped therein.

In the operation of this embodiment of the present invention, the arm 29 is first released from the fixed jaw 25 and swingable clamping jaw 28 is depressed in the

direction of fixed jaw 25. The clamp is then positioned over the edges of the material 40 to be joined, this material being received in the space between the legs on the U-shaped portion 27 on the clamp body and the fixed jaw 26 and movable clamping jaw 28 in the same manner as in the operation of the first embodiment of the invention and as shown in Figures 6 and 8. Movable clamping jaw 28 is then released and engages the material to be clamped as shown in Figure 8. Swinging arm 29 is then returned to the nested or jackknifed position as shown in Figure 8 and thereby compresses the spring 34 causing the full biasing force of this spring to be exerted on clamping jaw 28 to increase the gripping action of the clamp to a maximum.

The release of materials being clamped is accomplished by merely reversing the steps of the clamping operation set forth above with the exception that it will frequently be found unnecessary to manually depress the movable clamping jaw 28 prior to removing the clamp from the material.

A modification of the embodiment just described, which is shown in Figure 11, includes a clamp body similar to the clamp body 23 and having a fixed jaw 25' corresponding to the jaw 25 on the clamp 23. A clamping jaw 28' is pivotally mounted on a pivot pin 41 housed in an opening 42 in the fixed jaw 25' so as to be swingable in the same way as the clamping jaw 28 previously described. This swingable clamping jaw 28' is biased toward clamping position by a torsion spring 43 anchored at one end 44 in the swingable clamping jaw 28' and at the other end 45 in the pivot pin 41, the spring being stressed to bias the swingable jaw 28' in the same direction that the jaw 28 of the previous embodiment is biased. The biasing force of the spring 43 is also applied to a swinging arm 29' similar to arm 29 tending to pivot it outwardly of fixed jaw 25' because the ends of pivot pin 41 are swaged or otherwise fixed to the swinging arm 29' as indicated at 46. In other respects this modification of the invention may be the same as that previously described, and it operates in the same manner. It should be noted, however, that the swinging arm 29' may be omitted from this embodiment of the invention by anchoring the pivot pin 41 to fixed jaw 25' by any suitable means whereby the clamping action of the invention will still be effective although the means for varying the biasing force will be limited to depression of swingable clamping jaw 28' by the user.

It is to be understood that the forms of invention herein shown and described are to be taken as preferred examples of the same and that various changes in the shape, size and arrangement of parts may be resorted to without departing from the spirit of the invention or the scope of the subjoined claims.

I claim:

1. A clamp comprising a body having a generally U-shaped portion defining spaced generally parallel legs and an elongated projection on each leg, the longitudinal axes of said projections being substantially normal to said legs and both of said projections extending in like directions from corresponding regions of said legs and in substantially parallel planes so as to define fixed jaws disposed in opposed spaced relation, and movable clamping means pivotally mounted in the first of said fixed jaws and including means to move at least a portion of said movable clamping means toward and from clamping engagement with the second of said fixed jaws upon opposite pivotal movement of said movable clamping means with a variable force controllable by the user of the clamp.

2. A clamp comprising a body including portions defining elongated jaws and structure for fixedly holding said jaws in opposed spaced relation so as to define an unobstructed space between the opposed faces of the said jaws, a clamping jaw pivotally mounted upon said body and including a portion of substantial extent in the space

between the opposed faces of said fixed jaws conformed to be moved toward and from the inner opposed face of the first of said fixed jaws upon pivotal movement thereof so as to cooperate therewith in clamping and releasing material to be held by said clamp, an arm pivoted to swing outwardly of and to jackknife with the second of said fixed jaws on the side thereof opposite its opposed face, an expansion spring disposed between the contiguous sides of said pivoted jaw and pivoted arm so as to bias the said pivoted jaw in a clamping direction and the said arm away from jackknifed position and means for locking said arm in jackknifed position and thereby increasing to a maximum the compression of said spring and the resultant biasing force exerted by the said spring against said pivoted jaw.

3. A clamp comprising a body including portions defining elongated jaws and structure for fixedly holding said jaws in opposed spaced relation so as to define an unobstructed space between the opposed faces of the said jaws, a clamping jaw pivotally mounted upon said body and including a portion of substantial extent in the space between the opposed faces of said fixed jaws conformed to be moved toward and from the inner opposed face of the first of said fixed jaws upon pivotal movement thereof so as to cooperate therewith in clamping and releasing material to be held by said clamp, an arm pivoted to swing outwardly of and to jackknife with the second of said fixed jaws on the side thereof opposite its opposed face, an expansion spring reacting at opposite ends thereof against said pivoted jaw and said pivoted arm to bias the said jaw in a clamping direction and the said arm away from jackknifed position, means for releasably locking said arm in jackknifed position and thereby increasing to a maximum the compression of said spring and the resultant biasing force exerted by said spring against said pivoted jaw and means for limiting outward swinging movement of said pivoted arm.

4. A clamp comprising a body including opposed structure defining at least one fixed clamping jaw and fixed structure opposed thereto, a pair of elongated arms swingable upon a common axis in the structure opposed to said fixed jaw including a first arm having a portion opposed to said fixed jaw and swingable toward and from the same upon pivotal movement of the first arm and a second arm swingable toward and from the first, the said portion of said first arm being adapted to cooperate with said fixed jaw to clamp or release material to be held by the clamp upon pivotal movement of the said first arm, arcuate telescopically interconnected tubular members centered about said common axis, one of said tubular members being fixed to the first of said arms and the other to the second of said arms, an expansion spring housed in said tubular members for biasing said arms in opposite angular directions, and means for releasably locking the second arm at a position at which the maximum effective force of said spring is applied to said first arm.

5. A clamp comprising a body having substantially duplicate members having portions conformed to define clamping jaws and joined at one end thereof to define a clamp body having the configuration of an L in side elevation and a U in plan and end elevations, movable clamping means, and means to mount movable clamping means in one of said clamping jaws to effect movement thereof toward and from the other of said clamping jaws, there being vertical displacement between said clamping means and juncture of said duplicate members to permit vertical adjustment of said clamp when used to clamp material.

10 6. In a clamp a body comprising a generally U-shaped portion having elongated generally parallel legs and an elongated lateral projection adjacent the free end of each leg respectively, the longitudinal axes of said lateral projections being substantially perpendicular to the longitudinal axes of said legs and said lateral projections being disposed in substantially parallel spaced relation so as to form opposed fixed jaws extending to one side of said U-shaped portion and free of attachment to each other, movable clamping means and means to mount said movable clamping means in one of said laterally projecting fixed jaws for movement toward and from the other fixed 15 laterally projecting jaws including means controllable by the user of the clamp to vary the clamping force applied by the movable clamping means.

20 7. In a clamp a body comprising a generally U-shaped portion having elongated generally parallel legs and an elongated lateral projection adjacent the free end of each leg respectively, the longitudinal axes of said lateral projections being substantially perpendicular to the longitudinal axes of said legs and said lateral projections being disposed in substantially parallel spaced relation so as to form opposed fixed jaws extending to one side of said U-shaped portion and free of attachment to each other, one of said fixed jaws having a threaded aperture therein 25 30 35 40 45

one on an axis transverse to the longitudinal axes of both of said fixed jaws and movable clamping means having a shank in threaded engagement with said aperture so as to be movable toward and from the other of said fixed jaws upon rotation of the said clamping means relative to said body.
